(57) **CLAIM**

The ornamental design for a wet wipe packet as shown and described.

DESCRIPTION

FIG. 1 is a top perspective view of a wet wipe packet comprising the new design;

FIG. 2 is a top view of the design of FIG. 1;

FIG. 3 is a bottom view of the design of FIG. 1;

FIG. 4 is a front elevational view of the design of FIG. 1;

FIG. 5 is a back elevational view of the design of FIG. 1;

FIG. 6 is a left elevational view of the design of FIG. 1; and,

FIG. 7 is a right elevational view of the design of FIG. 1. The broken lines shown in the drawings depict portions of the wet wipe packet that form no part of the claimed design. The relatively light uneven broken lines shown in the figures represent surface contour only.

1 Claim, 4 Drawing Sheets
